UNITED STATES PATENT OFFICE

2,619,020

OVERHEAD FAN

Harry J. Bordé, Santa Monica, and Henry O. Fuchs, Los Angeles, Calif., assignors to Preco Incorporated, Los Angeles, Calif., a corporation of California

Application June 6, 1950, Serial No. 166,491

6 Claims. (Cl. 98—6)

1

This invention has reference to the design and structure of refrigerator cars equipped with forced air circulation; and the general purpose of the invention is to provide a structure and design for mounting and incorporating an air circulating fan of the type shown in the Van Dorn Patent No. 2,349,315 in refrigerator car bulkheads of, or similar to, standard design. Although certain features of the present invention have been designed particularly with a view to incorporation with a fixed bulkhead, it will be understood from what follows that the present showing of the invention in that environment is not to be considered as limitative.

For certain purposes it is desirable to locate the air circulating fan at a high level, preferably at the top of the bulkhead, rather than at the floor level or under the lading floor. Such a location removes the fan from the locality of falling debris in the ice bunker or in the lading compartment and thus serves to protect the fan from injury. The present invention provides a design for incorporating the fan structure in a standard type bulkhead structure, and thus, among other things, provides a fan design and structure which may be easily applied to existing car structures. Although the general features of the invention, as will be pointed out, may be used for incorporating the fan at any level in the bulkhead structure, it is particularly adapted for such incorporation at or near the top and will be so described in illustrative form.

For the purpose of describing a present preferred and illustrative embodiment of the invention, reference is made to the accompanying drawings in which:

Fig. 1 is a fragmentary side elevation of a car structure equipped with the illustrative embodiment;

Fig. 2 is a fragmentary cross-section taken substantially as indicated by line 2—2 on Fig. 1;

Fig. 3 is a horizontal section on lines 3—3 of Figs. 1 and 2; and

Figs. 4 and 5 are enlarged detail sections on lines 4—4 and 5—5 of Fig. 3.

The drawings show certain parts of a standard type of car structure, including the end and side wall formations 10 and 11, floor structure 12 and ceiling 22. A standard type of fixed bulkhead is shown fragmentarily at 13 in Figs. 1 and 2 and in horizontal and vertical section in Figs. 3—5. The plane on which the section of Fig. 2 is taken, and the fragmentarily compressed nature of Fig. 1, do not show the lower part of the bulkhead, but it will be understood that the bulk-

2

head structure extends down to the level of the lading floor or ice grate—a level above that of floor 12 so as to allow an air circulation opening under the bulkhead between the lading compartment and the ice bunker which the bulkhead defines.

The typical standard bulkhead structure shown in the drawings comprises a framing composed of spaced vertical studs 20 made of steel shapes, the outermost of which (20a) are bolted or otherwise secured directly to the side wall structures 11. At their upper ends these spaced studs are joined to a horizontal beam member, typically by bolting to such a beam member as shown at 21 in Figs. 4 and 5. Such beam member extends across the top of the bulkhead structure from side wall to side wall directly against the ceiling structure 22 and is tied into the ceiling structure as by having flanges 23 projecting into it.

On its outer side, facing the lading compartment, the bulkhead frame is usually faced with a wooden facing or apron 25 extending over the whole face of the frame structure except for an opening or openings at the top, directly under beam 21, and opening or openings at the bottom below the level of the ice grate or lading floor. On the inner side, facing the ice bunker space, the bulkhead frame is usually faced with a perforated sheet metal facing, such as shown at 26, normally extending to the top of the bulkhead. This facing is commonly installed in several separate sheets, of horizontal widths somewhat greater than the horizontal spacings between studs 20. The intermediate studs 20 are commonly made up of two channels secured together back-to-back; and the vertical edges of facing sheets 26 may be turned and clamped between them as shown in Fig. 3. At the outer vertical edges, where the outermost studs 20a are composed of single channels secured to the side wall structure, the outermost facing sheet edges may be clamped between the studs and the side walls, as shown in Fig. 3.

Such, in general, is the typical structure of a bunker-enclosing bulkhead to which the present invention applies an air impelling fan of the mentioned Van Dorn type. Insofar as the incorporation of the fan with the bulkhead structure is concerned it is immaterial whether the bulkhead is stationarily secured to the car floor, wall and roof structure or is mounted so as to be movable. Specifically, the bulkhead is here shown as fixed and the fan driving connections, later to be declared, are designed for that fixed position. If the bulkhead is of the convertible

or movable type, driving connections such as those shown in the application of Van Dorn and Beemer, Ser. No. 767,820, filed August 9, 1947, now Patent 2,544,242, dated March 6, 1951, may be used.

The air fan is preferably made up essentially of a series of radial bladed impellers 30 mounted in spaced relation on a common shaft 31 and surrounded by a casing which provides for air entry in a generally radial direction between the impellers, axial flow into the impellers, and horizontal radial out-flow from the impellers. In adapting the said type of fan for incorporation with such a standard bulkhead as described, the inter-impeller spacings are made commensurate with and preferably equal to the bulkhead stud spacings, the casing projects preferably rearwardly from the back or inner face of the bulkhead at the top so that the lateral air inflow is upward from the ice bunker into the casing from beneath, and the impeller sections of the casing are extended forwardly through the forward bulkhead facing between the studs for air discharge into the lading compartment. Preferred and illustrative details of structure and design will now appear.

The fan housing H comprises a main housing wall 35 of sheet metal bent to a cylindric arc of 90° and extending in length across the full width of the bulkhead. From substantially the upper edge of the arc formation an upwardly extending flange 36, along the whole length of the housing wall, is secured to the upper bulkhead beam 21 by bolts 37 which may be, or include, the bolts which secure the beam to the upper ends of the bulkhead studs. The relation of flange 36 to the axis of cylindric formation 35 is such as to place that axis (and the coincident axis of shaft 31) behind the rear face of the bulkhead. The main housing wall 35 also includes a skirt portion 38 which depends vertically from the lower edge of the cylindric formation. As seen in Figs. 3, 4 and 5, all the housing formation thus far described projects rearwardly from the rear face of the bulkhead into the upper part of the ice bunker-space. To reinforce that formation (of comparatively light sheet metal) against injury from anything introduced into the bunker through the roof hatch (not shown) its upper and rear part is reinforced with an extra thickness 39 of sheet metal welded or otherwise secured to it.

Also forming parts of the housing there is a series of pairs of transverse vertical division walls 40, each pair enclosing endwise one of the several spaced impeller chambers 56 in which the impellers 30 are located. These transverse walls are welded to the wall 35, 38 and the pairs project forwardly through the bulkhead structure between the spaced studs 20 and at least partially through the thickness of the forward facing or apron 25. A bottom plate 41 extends between the bottom edges of the pairs of walls 40 and also projects forwardly into the thickness of the apron 25. The side walls 40 may, as shown in dotted lines in Fig. 2, be integral with and bent upwardly from the opposite ends of bottom plates 41. And a top plate 42 lies on top of the upper edges of each of the pairs of walls 40, forward of flange 36 and extends forwardly at least to the rear face of apron 25. To facilitate the fitting of the fan housing, to accommodate small variations of dimensions, the forward extent of walls 40 and plates 41 is made such that their forward edges will lie somewhere within the thickness of apron 75

25. Then an angle flashing 41a is applied as shown in Fig. 4, to function as a seal between the discharge ends of the housing and the apron 25. From what has been said, and from Figures 3, 4 and 5, it will be seen that the pairs of transverse dividing walls 40, in association with the rear and upper main wall 35, 38 and the top and bottom plates 42 and 41, form compartments which enclose the several impellers 30, and which have forwardly extending open discharge ends extending in effect through the forward facing or apron 25 between studs 20. The open discharge ends are covered by screens 44.

An angle 46, extending the length of the housing, is welded to lower plates 41 and bolted, at 48, to studs 20. The whole casing, and its carried impellers and shaft, are thus secured in the described relation to the bulkhead by the two sets of bolts 37 and 48. The whole fan assembly is thus adapted to be quickly and easily mounted on the bulkhead after the front apron 25 has been formed with openings to accommodate the forwardly extending discharge passages, and the rear facing 26 has been cut out to a level below the lower housing plates 41. Figs. 2 and 4 show how the rear perforated facing is cut away, between studs 20, to an upper edge 26a, and how that upper edge is supported by blocks 47 inserted between studs 20. Bolts 49 hold the blocks and the facing 26 secure.

Impeller shaft 31 is carried in bearings 50 which are carried on brackets 51 mounted on housing wall 35. The bearings locate the shaft on the axis shown and also longitudinally.

25 In the specific design here shown, the impellers 30 and their chambers 56 which lie between the pairs of transverse walls 40, are located substantially centrally of the spaces between the several bulkhead studs 20. The spaces 55 in the housing structure between the several impeller chambers are enclosed only by the main housing wall 35, 38, the apron 25, and the two adjacent lateral division walls 40. See Fig. 5. In those spaces 55 there is no lower plate 41, so that those spaces form air entry chambers which are completely open at their bottoms for upward air entry both behind the plane of the perforated facing 26 and forward of that plane in the spaces between the studs behind front apron 25. Each lateral wall 40 has a large opening 40a co-axial with the impeller shaft. Air thus enters the fan casing exclusively in an upward flow into the air entrance chambers 55 between the impeller chambers 56, flows axially through openings 40a into the impellers and is thrown out by the impellers through the open forward ends of the impeller chambers into the lading compartment. The fact that the housing H is open for air entry only at its bottom and that air enters only in an upward flow, protects the fan mechanism quite completely from ice or debris which might otherwise enter the housing and damage the impellers.

As seen in Fig. 5, the air entry spaces 55 also do not have any upper plate corresponding to upper plate 42 (Fig. 4) of the impeller chambers. While the chambers 55 might also have such upper enclosing plates, they are unnecessary because the upper beam 21 effectively closes what would otherwise be an opening into the tops of those spaces and through which solid matter might enter.

It will be noted that the general arrangement is such that it sets up a "reverse" air flow through the ice bunker, the air stream being drawn up through the ice charge and thrown out into the

lading compartment under the ceiling. That direction of air flow is desirable. On the other hand, if it should be desirable to circulate the air in the opposite or "natural" direction (down through the ice charge) that can be accomplished, using the same type of fan structure and incorporation with the bulkhead, by simply turning the fan structure end-for-end and mounting it on the front face of the bulkhead with its impeller chambers projecting through the apron between the studs. However, that would involve the projection of the fan housing into the lading compartment, which in many cases is undesirable.

Also it will be noted that the structure and design for incorporation of the fan with the bulkhead structure, have no features which would prevent the fan being mounted on the bulkhead at any level below its top, or even at or near its bottom. While the top location, and air entry from underneath into a fan casing which overhangs in the ice bunker is preferred, and while the structure and design of the invention have been made with that particularly in view, the general structure and design are equally applicable to mounting the fan at or near the bottom of the bulkhead without any essential change in the structure. If so mounted at the bottom, with air intake on the ice bunker side, the air current would then be drawn down through the bunker and discharged horizontally near or at the level of the car floor. If, in that lower position, the fan were turned end-for-end and mounted to project on the lading compartment side of the bulkhead (as above explained for top mounting) the air would be drawn from the lading compartment and discharged into the lower part of the bunker to flow up therethrough.

For driving the impeller fan mounted as described on the upper part of a bulkhead which is stationary, the following described driving arrangements are preferred.

Impeller shaft 31 is extended outwardly through one side wall 11 (Figs. 2 and 3) through a sleeve 60 and a seal 61. The outer end of the shaft, projecting into a chamber under a cover 62, carries a sheave 63 driven by belt 64 from a sheave 65 on a jack-shaft 66 mounted in a journal 67 carried on the end of a swinging arm 68 which is pivoted in a bracket structure 69 mounted in a casing recessed in the car side wall behind the side wall sheathing 70. Arm 68 is pressed down by spring 71 in a direction to keep belt 64 taut. The hub 65a of sheave 65 is accessible from outside the casing, through an opening 62a in cover 62 so that an auxiliary drive may be applied for driving the air circulated fan while the car is standing. (See Van Dorn application, Ser. No. 643,924, filed January 28, 1946, now abandoned.) Another sheave 75 is carried by jack-shaft 66 and is driven by belt 76 from a sheave 77 mounted on the outer end of a drive shaft 78 journaled in a tubular shaft carrier 79. (The drive mechanism here now being described is of the general type shown and claimed in the Van Dorn Patent 2,413,158 and more particularly of the type shown and claimed in the copending applications of Beemer and Fuchs, Ser. No. 667,803, filed May 7, 1946, now Patent 2,519,170, dated Aug. 15, 1950, and Ser. No. 162,198, filed May 16, 1950, now Patent 2,567,504, dated September 11, 1951. See particularly the latter application for the particulars of the drive mechanism here shown.)

The inner end of drive shaft 78 carries a traction roller 80 adapted to engage car wheel 81 when shaft carrier 79 is pressed down; that same

downward pressure on the carrier and shaft serving to keep driving belt 76 taut. The carrier is so mounted by an arm structure 82, on a mounting shaft 83 journaled under the car floor, that rotation of the mounting shaft swings the shaft carrier 79 as a whole up and down about the axis of the mounting shaft, and so that the carrier 79 and shaft 78 can also swing about the axis indicated by the line A in Figs. 1 and 2. A torsion spring 84, located in hollow mounting shaft 83 and connected at one end at 85 with a bracket 86 on a cover casing 74 and at its other end at 87 with the mounting shaft, tends to rotate shaft 83 counter-clockwise in Fig. 1 and to press carrier 79 down to keep roller 80 in traction engagement and belt 76 taut. Rotation of shaft 83 clockwise, arm structure 82 swinging with it, lifts shaft carrier 79 to relieve belt 76 and the traction pressure of roller 80. A lifting arm 90 is connected to mounting shaft 83 through a lug 91 in such manner that, when arm 90 is moved from the full line to the broken line position of Fig. 1, shaft 83 is rotated to lift the shaft carrier, and the arm also moves up under the outer end of the carrier to insure the lifting of sheave 77 and the loosening of belt 76.

All of the immediately foregoing is the subject matter of said copending applications and patents and is there described in detail. In the present drive arrangement, however, when belt 76 is relieved, belt 64 is still held taut by the spring 71 acting on jack-shaft 66 and sheave 65, so that an auxiliary drive can then be applied to the hub of either sheave 65 or sheave 63.

We claim:

1. In combination with a wall structure including a series of horizontally spaced vertical studs with a substantially continuous facing on one side of the studs, a fan structure incorporated with the wall structure and including a fan housing comprising an external top and side housing wall extending horizontally across the wall structure and projecting from one side thereof, horizontally spaced pairs of horizontally spaced vertical walls dividing the housing interior into alternating impeller and intake compartments, walls forming tops and bottoms for the impeller compartments, said top and bottom walls and the vertical walls associated therewith extending through the facing of the wall structure between adjacent studs and defining horizontal outlet passages from the impeller compartments to the other side of the wall structure, there being air-entry openings at the under sides of the several intake compartments, an impeller shaft extending horizontally through the interior of the housing externally of the wall structure and through the several vertical division walls, said division walls being provided with openings, and impellers on the shaft in each of the several impeller compartments, the openings in the vertical division walls providing communication between the intake compartments and the impeller compartments.
2. In a refrigerator car or the like having a bulkhead which separates two compartments, said bulkhead comprising a frame which includes a plurality of horizontally spaced vertical studs and a substantially continuous facing on one side of the frame; the combination of an air fan unit extending in length horizontally across the bulkhead width on the other side of the frame, said unit including a top and side casing wall projecting from said other side of the frame, a series of vertical division walls spaced along the length

of the top and side wall, said division walls extending at least partially through the facing on the one side of the frame and defining within the top and side wall alternating air intake compartments and impeller compartments, a top and a bottom wall for each of the impeller compartments and extending at least partially through said facing to form, with the associated vertical division walls, open ended air discharge passages from the impeller compartments, there being air-entry openings at the undersides of the several intake compartments, a horizontal impeller shaft extending through the length of the air fan unit and through the several vertical division walls, said division walls being provided with openings providing communication between the intake compartments and the impeller compartments, and impellers on the shaft in the several impeller compartments.

3. The combination defined in claim 2 and in which the bulkhead frame includes a horizontal beam extending across the tops of the spaced studs, the top wall of the casing being secured at an upper edge to said beam, and an angle plate extending in length across the said other face of the frame under the said bottom walls and secured thereto and to the several vertical studs.

4. In a refrigerator car or the like having a vertical transverse bulkhead which separates an ice bunker at its inner face from a lading compartment at its outer face, the combination of an air circulating fan unit comprising a housing which extends in length horizontally across the inner face of the bulkhead near its top and projects inwardly into the ice bunker from that bulkhead face, said housing comprising vertical walls and top, horizontal walls which define air entry passages, there being air-entry openings at the undersides of the several air-entry passages,

vertical walls and top and bottom horizontal walls which define air exit passages extending to openings provided through the bulkhead to discharge air into the lading compartment, 5 there being openings through certain of said vertical walls whereby communication is established between the air-entry passages and the air-exit passages, and air impeller means in the housing acting to draw air in through the air entry passages and force it out through the air exit passages.

5. The combination defined in claim 4 and in which the bulkhead includes a frame comprising horizontally spaced vertical studs and a facing on the lading compartment side of the studs, and in which the wall-defined air exit passages extend through the bulkhead between adjacent studs and extend at least partially through said facing.

6. The combination defined in claim 5 and in which the inner face of the bulkhead frame also has a facing, said last named facing being terminated at an upper horizontal edge which is spaced below the wall-defined air entries.
